LAW GROUP LLP(57) **CLAIM**

The ornamental design for a mixing tap, as shown and described.

DESCRIPTION

FIG. 1 is a bottom plan view of a mixing tap showing my new design;

FIG. 2 is a front elevational view thereof;

FIG. 3 is a top plan view thereof;

FIG. 4 is a left-side elevational view thereof;

FIG. 5 is a right-side elevational view thereof;

FIG. 6 is a top, front, right-side perspective view thereof; and,

FIG. 7 is a rear elevational view thereof.

The broken lines in the drawings depict portions of the mixing tap that form no part of the claimed design.

1 Claim, 7 Drawing Sheets(56)
